DRIER CYLINDER

Paul M. F. Buettner, Oakland, Calif.

Application July 5, 1932, Serial No. 620,741

16 Claims.

(Cl. 34—4)

This invention is a drier cylinder which is especially adapted to the usual calenders or driers as at present form standard equipment in public laundries and paper plants and similar institutions, although it is also adaptable for use in the smaller sizes of drier cylinders.

Considerable difficulty is encountered in the present types of steam heated drier cylinders, to obtain uniform heat throughout the roll or cylinder.

The drier cylinder which is the subject of this application is designed for the specific purpose of obtaining uniform heat throughout the length and periphery of the cylinder and also provides a distribution system within the roll for carrying the steam to various portions of the roll.

The main object of the invention, therefore, is to provide a drier cylinder with means for providing a complete circulation of steam so as to obtain uniform heating throughout the entire periphery of the roll.

Another object of the invention is to provide a distribution system within the cylinder for distributing the steam directly to the inner periphery of the cylinder and at different points throughout the length and periphery thereof.

A further object of the invention is to provide the means as outlined with means for centering the distribution means within the cylinder, this means being adjustable from without the cylinder.

Other objects and advantages of the invention will become apparent as the following description is read on the drawings forming a part of this specification and in which similar reference characters are used to designate similar parts throughout the several views, of which:

Fig. 1 is a sectional elevation through the cylinder with part of the steam distributing means shown in section.

Fig. 2 is an end view of one of the equalizing shoes.

Fig. 3 is an end elevation of the invention showing a portion broken away to show the centering means for the steam distributor.

Fig. 4 is an enlarged end view of one of the centering devices.

Fig. 5 is a side view of Fig. 4 with one of the guide rods removed so as to show the adjusting screw.

The invention consists of a drier cylinder 10 provided with removable heads 11 and 12 which are suitably secured by means of screws 13, suitable packing being provided between the heads and the roll. The head 11 is provided with a hollow trunnion 14 and the head 12 is provided

with a solid trunnion 15, whereby the cylinder is rotatably mounted for operation.

Mounted within the cylinder 10 is a drum 16 having heads 17 and 18 which are suitably secured to the drum 16. Adjacent to trunnion 14 a concentric collar 19 is provided into which the steam is directed from the trunnion 14. This collar may be of any suitable length and may extend substantially to the head or may be spaced therefrom. Where the collar extends forwardly, it is necessary to provide a slot to clear the water discharge pipe 20 which passes through the trunnion 14 and through which the water of condensation is removed. However, it is preferable to make the collar 19 sufficiently short so as not to interfere with the pipe 20 so that the pipe 20 may be retained in a vertical position so as to have the lower end always submerged in the water of condensation, in which event the collar would be of a length extending substantially to the pipe 20.

The interior of drum 16 is entirely closed to the interior of the cylinder and has a connection 21 communicating to the exterior of the drum, this connection being preferably formed of flexible pipe or hose and is intended for the purpose of equalizing the air pressure within the drum.

Diagonally extending from the head 18 of the drum, within the area defined by the collar 19, are a plurality of tubes 22 which terminate in the periphery of the drum 16 as is indicated at 23 and which are intended to receive the steam through the collar 14 and direct this steam to different points along the cylinder 10. It will be observed that the tubes 22 are of different lengths, although they all diverge from the vicinity of the collar 19.

The centering means for the drum consists of a plurality of adjustable members, each of which consists of a shoe 24 which has fixedly secured thereto a pair of guides 25, which guides are slideable in bearings formed in brackets 26 and 27 which are suitably secured to the head 17. Mounted in the periphery of the shoes 24 are a plurality of auxiliary shoes 28 which are urged outwardly by springs 29, these auxiliary shoes 28 being suitably retained on the main shoes 24 in such manner as to permit resilient action against the interior of the cylinder.

Fixedly mounted in the shoe 24 is a screw 30 which cooperates with a nut 31 which is retained between the brackets 26 and 27 and preferably provided with journals rotatable in suitable bearing bores in the brackets 26 and 27, this nut being provided with an internal thread for cooperation with the screw 30, and being externally provided

with bevel gear teeth 32 forming a bevel pinion for cooperation with a bevel gear 33, which is rotatably mounted on the head 17 and guided by means of rollers 34, which rollers are rotatably mounted on studs 35 so as to permit free action of this bevel gear. This bevel gear is also provided with internal gear teeth 36 with which a spur pinion 37 cooperates for adjustment. A groove 38 is formed in the back of the bevel gear 33 for cooperation with the rollers 34.

10 A plurality of these units are provided at each end of the drum, and are equally spaced and operate in unison. The pinions 37 are mounted on a shaft 39, which extends throughout the length 15 of the drum, and has a projecting wrench end 40, which is accessible through a hand hole 41 formed in the head 11, which hand hole is normally closed by the usual means.

In assembling the device, it is merely necessary 20 to adjust the shoes 24 back sufficiently to permit insertion in the roll 10, following which the shaft 39 is rotated in the proper direction by means of a wrench applied on the end 40, through the hand hole 41. The shoes 28 thus all come into contact 25 simultaneously and as the shoe 24 is adjusted further out, the springs 29 are compressed, and these springs readily take up any variations in the diameters of the shells thus compensating for expansion and contraction. A suitable spacing 30 device is provided, the same consisting of brackets 42 and 45, one secured to one end of the core and the other secured to the adjacent end of the cylinder but eccentrically positioned with the first bracket, and a link connecting said 35 brackets permits rotation of the drum relative to the cylinder, and yet retains the end of the drum in fixed relation to the head 12. The connection 21 between the outer air and the drum prevents 40 rupture of the inner drum by expansion of gases, which might be entrapped therein or the possibility of creation of vacuum therein as this drum is entirely sealed out of communication with the interior of cylinder 10.

The steam for heating the cylinder enters 45 through the trunnion 14, which trunnion preferably extends to a point within the head to suitably clear the pipe 20, so as to permit the cylinder 10 and drum 16 to rotate independently of this pipe, so that the pipe may be retained in a vertically downward position. The steam after passing 50 through the trunnion 14, enters the pipes 22 at 43, passing through these pipes into the space 44 between the drum and the cylinder, thus directing the steam to various points about the 55 periphery of the cylinder 10. The steam which is condensed, gathers in the lower part of the cylinder 10 and is forced out through the pipe 20 by the steam pressure within the cylinder.

It has been found that a better distribution of 60 the heat is provided by the device outlined and that a far more satisfactory type of work can be produced in a cylinder built according to my method than by any other means now known. It will be noted that positive centering of the 65 drum can be obtained within the cylinder and that this centering device is adapted to compensate for variations due to expansion or contraction, and that due to the number of contacting faces provided, that positive driving of the drum 70 in conjunction with the cylinder is provided.

Having described an operative device, it will be understood that variations in the construction and arrangement of parts which are consistent with the appended claims may be resorted to 75 without detracting from the spirit or scope of the

invention or sacrificing any of the advantages thereof:

I claim:

1. A drier cylinder provided with a hollow internal, axially disposed core, closed at its ends said core being internally in communication with the atmosphere to compensate for thermal expansion and contraction of the gases contained therein and being provided to restrict the steam space within the cylinder.

5 10 15 20 25 30 35 40 45 50 55 60 65 70 75 80 85 90 95 100

2. A drier cylinder comprising a cylinder and a removable head for each end thereof, a trunnion integral with one head and a journal integral with the other head, a closed hollow core within said cylinder and forming a restricted steam space between the core and cylinder, expansion and contraction compensating mounting means for said core within said cylinder, an air passage between the interior of the core and the exterior of the cylinder to maintain atmospheric pressure within the core under variations in temperature, and, a plurality of diagonal steam passages through the core and extending from one end adjacent the trunnion to different points about the periphery of the core to cause steam to angularly impinge on the inner surface of the cylinder and be directed longitudinally thereof.

3. A drier cylinder comprising a cylinder and a removable head for each end thereof, a trunnion integral with one head and a journal integral with the other head, a closed hollow core within said cylinder and forming a restricted steam space between the core and cylinder, expansion and contraction compensating mounting means for said core within said cylinder, an air passage between the interior of the core and the exterior of the cylinder to maintain atmospheric pressure within the core under variations in temperature, and, a plurality of diagonal steam passages through the core and extending from one end adjacent the trunnion to different points about the periphery of the core to cause steam to angularly impinge on the inner surface of the cylinder and be directed longitudinally thereof, said mounting means consisting of a plurality of equi-angularly spaced, radially adjustable members mounted on each end of the core, and means for coincidentally adjusting all of said members for centering the core within the cylinder, each of said members having a plurality of spring urged auxiliary shoes to provide multi-point resilient cooperation of each member with the surface of the cylinder.

4. A drier cylinder comprising a cylinder and a removable head for each end thereof, a trunnion integral with one head and a journal integral with the other head, a closed hollow core within said cylinder and forming a restricted steam space between the core and cylinder, expansion and contraction compensating mounting means for said core within said cylinder, an air passage between the interior of the core and the exterior of the cylinder to maintain atmospheric pressure within the core under variations in temperature, and, a plurality of diagonal steam passages through the core and extending from one end adjacent the trunnion to different points about the periphery of the core to cause steam to angularly impinge on the inner surface of the cylinder and be directed longitudinally thereof, said mounting means consisting of a plurality of equi-angularly spaced, radially adjustable members mounted on each end of the core, and means for coincidentally adjusting all of said members

for centering the core within the cylinder, each of said members having a plurality of spring urged auxiliary shoes to provide multipoint resilient cooperation of each member with the surface of the cylinder, said members each consisting of a shoe, a pair of parallel guides for each shoe, a screw interposed between the guides and having one end fixed in the shoe, a rotatable threaded bevel pinion on said screw, and means for retaining said pinion against radial movement, said auxiliary shoes being mounted on the outer face of the shoe.

10. for retaining said pinion against radial movement, said auxiliary shoes being mounted on the outer face of the shoe.

5. A drier cylinder comprising a cylinder and a removable head for each end thereof, a trunnion integral with one head and a journal integral with the other head, a closed hollow core within said cylinder and forming a restricted steam space between the core and cylinder, expansion and contraction compensating mounting means 15 for said core within said cylinder, an air passage between the interior of the core and the exterior of the cylinder to maintain atmospheric pressure within the core under variations in temperature, and, a plurality of diagonal steam passages 20 through the core and extending from one end adjacent the trunnion to different points about the periphery of the core to cause steam to angularly impinge on the inner surface of the cylinder and be directed longitudinally thereof, said 25 mounting means consisting of a plurality of equi- angularly spaced, radially adjustable members mounted on each end of the core, and means for coincidently adjusting all of said members for centering the core within the cylinder, each of 30 said members having a plurality of spring urged auxiliary shoes to provide multi-point resilient cooperation of each member with the surface of the cylinder, said members each consisting of a shoe, a pair of parallel guides for each shoe, a screw interposed between the guides and having one end fixed in the shoe, a rotatable threaded bevel pinion on said screw, and means for retaining said pinion against radial movement, said auxiliary 35 shoes being mounted on the outer face of the shoe, said means for coincidently adjusting all of said members consisting of a bevel gear rotatably mounted at each end of the core and concentrically therewith and meshing with all of the bevel pinions at its respective end of the core, an internal gear formed in each bevel gear, a spur pinion meshing with each internal gear, a 40 shaft having said spur pinions fixed thereon, said shaft being rotatably mounted in the core and having a projecting wrench end at one end accessible through a hand hole formed through the cylinder head.

40. screw interposed between the guides and having one end fixed in the shoe, a rotatable threaded bevel pinion on said screw, and means for retaining said pinion against radial movement, said auxiliary shoes being mounted on the outer face 45 of the shoe, said means for coincidently adjusting all of said members consisting of a bevel gear rotatably mounted at each end of the core and concentrically therewith and meshing with all of the bevel pinions at its respective end of the core, an internal gear formed in each bevel gear, a 50 spur pinion meshing with each internal gear, a shaft having said spur pinions fixed thereon, said shaft being rotatably mounted in the core and having a projecting wrench end at one end accessible through a hand hole formed through the cylinder head.

6. Mounting means for a core within a cylinder comprising; a plurality of equi-angularly spaced, radially adjustable members mounted on each end of the core, and means for coincidently adjusting all of said members for centering the core within the cylinder, each of said members having a plurality of spring urged auxiliary shoes to provide multi-point resilient cooperation of each member with the surface of the cylinder.

7. Mounting means for a core within a cylinder comprising; a plurality of equi-angularly spaced, radially adjustable members mounted on each end of the core, and means for coincidently adjusting all of said members for centering the core within the cylinder, each of said members having a plurality of spring urged auxiliary shoes to provide multi-point resilient cooperation of each member with the surface of the cylinder, said members each consisting of a shoe, a pair

of parallel guides for each shoe, a screw interposed between the guides and having one end fixed in the shoe, a rotatable threaded bevel pinion on said screw, and means for retaining said pinion against radial movement, said auxiliary 5 shoes being mounted on the outer face of the shoe.

8. Mounting means for a core within a cylinder comprising; a plurality of equi-angularly spaced, radially adjustable members mounted on each end of the core, and means for coincidently adjusting all of said members for centering the core within the cylinder, each of said members having a plurality of spring urged auxiliary shoes to provide multi-point resilient cooperation of each member with the surface of the cylinder, said members each consisting of a shoe, a pair of parallel guides for each shoe, a screw interposed between the guides and having one end fixed in the shoe, a rotatable threaded bevel pinion on said screw, and means for retaining said pinion against radial movement, said auxiliary 15 shoes being mounted on the outer face of the shoe, said means for coincidently adjusting all of said members consisting of a bevel gear rotatably mounted at each end of the core and concentrically therewith and meshing with all of the bevel pinions at its respective end of the core, an internal gear formed in each bevel gear, a spur pinion meshing with each internal gear, a 20 shaft having said spur pinions fixed thereon, said shaft being rotatably mounted in the core and having a projecting wrench end at one end accessible through a hand hole formed through the cylinder head.

9. A drier comprising a cylinder having removable end walls provided with trunnions, a cylindrical core concentrically located within said cylinder and provided with normally closed ends, said core having a plurality of diagonally disposed steam passages diverging from one end of the drum to the periphery thereof, adjustable means for removably supporting the core within the cylinder, means for venting said core, and means for introducing steam into said steam 45 passages.

10. A drier comprising a cylinder having removable end walls provided with trunnions, a cylindrical core concentrically located within said cylinder and provided with normally closed 50 ends, an annular collar on one end of said core, means providing a plurality of divergent steam passages leading from the area encircled by said collar to the periphery of said core, means for venting said core, means for removably supporting said core within the cylinder, and means for introducing steam into said steam 55 passages.

11. A drier comprising a cylinder having removable end walls provided with trunnions, one of said trunnions being hollow and communicating with the interior of the cylinder, a cylindrical core located within the cylinder, adjustable means for removably supporting the core within the cylinder, means providing a plurality of steam 60 passages arranged in divergent relation with their inlet ends in one end of the core adjacent said hollow trunnion, their outer ends being located at different distances along the periphery of the core, means for venting said core, and means for introducing steam into said passages through said 65 hollow trunnion.

12. A drier comprising a cylinder having removable end walls provided with trunnions, a cylindrical core concentrically located within said cylinder and provided with normally closed ends,

- means for heating the core, brackets secured to the ends of the core, screw shafts adjustably mounted in said brackets and each provided with a shoe constructed and arranged to bear against the interior of the cylinder, adjusting rings rotatively supported by said brackets, said rings having internal rack teeth there being one ring at each end of the core, said rings and said screw shafts having complementary means so constructed and arranged that adjustment of all of the shoes relative to the cylinder is simultaneously effected by rotative movements of said rings, and means normally engaging said rack teeth for simultaneously rotating said rings.
13. A drier comprising a cylinder having removable end walls provided with trunnions, a cylindrical core concentrically located within said cylinder and provided with normally closed ends, means for heating the core, brackets secured to the ends of the core, screw shafts adjustably mounted in said brackets and each provided with a shoe constructed and arranged to bear against the interior of the cylinder, auxiliary shoes yieldably engaging the first-mentioned shoes, guides secured to the first-mentioned shoes and slidably engaging said brackets, adjustable rings supported by said brackets, there being one ring at each end of the core, said rings and said screw shafts having complementary means so constructed and arranged that simultaneous adjustment of all of the shoes relative to the cylinder is effected by rotative movement of the rings, and means for simultaneously rotating said rings.
14. A drier comprising a cylinder having removable end walls provided with trunnions, a cylindrical core concentrically located within said cylinder and provided with normally closed ends, means for heating the core, brackets secured to the ends of the core, screw shafts adjustably
- mounted in said brackets and each provided with a shoe constructed and arranged to bear against the interior of the cylinder, rollers carried by said brackets, adjustable rings, one at each end of the core, said rings each having channels engaging said rollers in such manner as to rotatively support the rings, said rings and the screw shafts having complementary means so constructed and arranged that adjustment of the shoes relatively to the cylinder is simultaneously effected by rotative movement of the rings, and means for simultaneously rotating said rings.
15. A drier comprising a cylinder having removable end walls provided with trunnions, a cylindrical core concentrically located within said cylinder and provided with normally closed ends, brackets secured to the ends of said core, nuts rotatively mounted in said brackets, said nuts having peripheral teeth, screw shafts engaging said nuts, shoes secured to said screw shafts and so positioned as to bear against the interior of the drum, adjuster rings rotatively supported by the brackets, there being one ring for each end of the core, said rings having teeth engaging said nuts in such manner that rotative adjustment of the rings will simultaneously effect adjustment of the shoes relative to the cylinder, and means for simultaneously rotating said rings.
16. In a drier, a normally closed cylinder, a closed core removably supported within the cylinder, a bracket secured to one end of the core, a second bracket secured to an adjacent end of the cylinder but eccentrically disposed with respect to the first bracket, and a link connecting said brackets in such manner as to maintain said end of the core in spaced relation with respect to said adjacent cylinder end.

PAUL M. F. BUETTNER.
